W. RAYMOND

GOVERNOR FOR STEAM DRIVEN COMPRESSORS

Filed Nov. 6, 1925

Patented Sept. 20, 1927.

1,643,129

UNITED STATES PATENT OFFICE.

WARD RAYMOND, OF EASTON, PENNSYLVANIA, ASSIGNOR TO PENNSYLVANIA PUMP AND COMPRESSOR COMPANY, OF EASTON, PENNSYLVANIA, A CORPORATION OF PENNSYLVANIA.

GOVERNOR FOR STEAM-DRIVEN COMPRESSORS.

Application filed November 6, 1925. Serial No. 67,316.

This invention relates to compressors and in particular to a governor for an air compressor or vacuum pump directly driven from a steam engine.

5 An object of the present invention is to provide an improved form of governor for a steam engine directly connected to and adapted to drive a compressor.

Another object of the invention is to provide a throttling governor of a steam engine with means for closing, or partly closing, the steam admitting valve of the engine when the speed of the engine exceeds a predetermined maximum, when the receiver pressure exceeds a predetermined maximum while the compressor continues to operate under load, and when the unloaders have operated to release the load from the compressor.

20 A further object of the invention is to provide three independently operating means for controlling the position of the steam supplying valve of an engine to regulate the amount of steam supplied to operate a compressor.

25 And finally it is an object of the invention to provide two pressure controlled regulating means for a steam engine valve which may be independently controlled and adapted to throttle the steam admitted to the engine down to predetermined limited amounts.

30 With the above and other objects of the invention in view, my invention consists in the features of construction and operation set forth in the following specification and 35 illustrated in the accompanying drawing.

In the accompanying drawing annexed hereto and forming a part of this specification, I have shown my invention embodied in a single cylinder steam driven compressor, 40 but it will be understood that the drawing is not to be construed as defining or limiting the scope of the invention, the claims appended to this specification being relied upon for that purpose.

45 In the drawing:

Figure 1 is a side elevation of a complete steam engine compressor having the present invention applied thereto.

50 Fig. 2 is a view in elevation of the throttling valve of a steam engine and governor therefor, some parts being shown in section, and

Fig. 3 is a plan view in section taken upon line 3—3 of Fig. 2.

In the above mentioned drawing, I have 55 shown but one embodiment of the invention which is now deemed preferable, but it is to be understood that changes and modifications may be made within the scope of the appended claims without departing from the 60 spirit of the invention.

Briefly, and in its broadest aspect, my invention comprises the following principal parts: first, a compressor; second, an unloader of any preferred type therefor; third, 65 a steam engine coupled to the compressor; fourth, a steam admitting valve for said engine; fifth, centrifugal speed governing means adapted to control the position of said valve; sixth, pressure operated means to control the position of the valve and connected to the receiver or discharge opening of the compressor; seventh, pressure operated 70 means to control the position of the valve and operated in connection with the unloading of the air cylinder; and eighth, means to limit the closing movement of said valve when controlled by said pressure operated 75 means.

Referring more in detail to the figures of 80 the drawing, I show at 10 a compressor directly attached to and operated by a steam engine 11. As the construction of the compressor 10 and the steam engine 11 may be of any preferred or usual construction, they 85 will not be described in detail. It will suffice to state that the compressor 10 has a discharge outlet 12 and an intake at 13. To the intake is attached an unloader 14 which may be similar to that described in my Patent 1,510,161, granted Sept. 30, 1924.

The engine 11 is provided with a steam supply conduit 15 having a main steam admission valve casing 16. Within the casing 16 is a valve 17, preferably of the balanced 95 type, movable vertically to vary the opening to admit steam to the engine in the usual manner. As shown the valve 17 is on the lower end of a vertical rod 18 passing through a suitable stuffing box (not shown) 100 so that vertical movement of the rod 18 will vary the amount of steam admitted to the engine.

In order to control the admission of steam in accordance with the speed of the engine, 105 a centrifugal governor 19 of the fly-ball type is attached at the upper end of the rod 18. This governor 19 is adapted to be driven

through bevel gears 20 from the crank shaft 21 of the engine by means of a belt 22. Increased speed of the engine crank shaft 21 causes the balls of the governor 19 to move outward and thus force the rod 18 downward to close the valve 17. Reduced speed causes the balls to move inward and so cause the rod 18 to move upward and the valve 17 to open.

On the rod 18 is a collar 24 suitably fastened thereto. On this collar 24 rests one end of a lever 25 pivotally supported on the frame 26 of the governor 19. This end of the lever 25 is forked so that it engages the collar 24 on opposite sides of the rod 18. It will be seen from this construction that oscillation of the lever 25 will force the rod 18 downward to close the valve 17 but will not interfere with downward movement of the rod 18 by the action of the centrifugal governor 19.

To oscillate the lever 25 to force the rod 18 downward, two arms 27 are provided pivoted at one end to the frame 26. Each of these arms carries an adjustable weight 28. Also the arms 27 are independently mounted so that they may be moved individually. The lever 25 at its end away from the rod 18 is formed with an integral cross bar 29 so that upward movement of either of the arms 27 will oscillate the lever 25 to force the rod 18 downward.

Below one of the arms 27 is a small cylinder 30 within which operates a piston to force a piston rod 31 and the arm 27 upward when sufficient pressure is admitted within the cylinder 30. The pressure within the cylinder 30 necessary to raise the arm 27 above it is governed by the position of the weight 28. To admit pressure to the lower end of the cylinder 30 a conduit 32 leading directly to the discharge conduit 12 of the compressor 10 is provided. It will be seen therefore that as soon as sufficient pressure has been created within the discharge pipe 12, an arm 27 will be elevated by upward movement of the piston rod 31. This oscillates the lever 25 to lower the rod 18 and reduce the amount of steam admitted to the engine. The speed of the engine is therefore reduced as soon as a critical pressure has been built up in the discharge conduit 12.

Below the other arm 27 is another cylinder 33 similar in every way to cylinder 30 and having a piston rod 34 moved by its piston within cylinder 33 when pressure is admitted thereto. For this purpose a conduit 35 is attached to the cylinder at one end and at its opposite end is in connection with a conduit 36 from a pilot valve 37 to an unloader 14. The pilot valve 37 as shown is connected by conduit 38 to the discharge conduit 12. When the pressure within the conduit 12 is sufficient to operate the pilot

valve 37, which may be similar to that shown in my Patent 1,523,716, granted January 20, 1925, pressure is admitted to the intake unloader 14 to relieve the compressor of its load. Simultaneously this pressure is admitted to conduit 35 and to the cylinder 33 to elevate its arm 27.

Above each arm 27 is an adjustable screw 39 suitably supported by the frame 26 to limit the upward movement of the arm 27. The arms 27 can therefore be individually adjusted to close the valve 17 to predetermined amounts.

In practice the arm 27 operated by receiver or discharge pressure directly through conduit 32 is adjusted to close the valve 17 sufficiently to operate the engine at a greatly reduced speed but still sufficiently fast to prevent it from stopping on a dead center while the compressor 10 is still operating in its loaded or operating condition. If the discharge pressure continues to rise while the engine is being run at this reduced speed the pilot valve 37, adjusted for a slightly higher pressure than that necessary to operate the piston within cylinder 30, opens to admit pressure to the unloader 14. When the load is thus suddenly taken from the compressor the speed of the engine 11 has a tendency to rise, which tendency is checked by operation of the piston rod 34. With the compressor 10 operating in unloaded condition, that is, while it is idling, the engine 11 can be run at a still further reduced speed without danger of its stopping on dead center. The arm 27 operated by pressure within cylinder 33 through conduit 35 and the pilot valve 37 may therefore be set to close the valve materially further than the arm 27 operated by pressure within cylinder 30.

From the above it will be seen that three independently adjustable means are provided to vary the position of the throttle valve 17 of an engine, one of which is operated by the speed of the engine and the other two by different discharge pressures delivered by the compressor. One of these pressure operated means is directly operated by discharge pressure and the other, preferably at a slightly higher discharge pressure is operated through a pilot valve controlling an unloader. In this way the steam admitted to the engine to maintain the engine operating at reduced speed is controlled when the compressor is operating normally and at maximum pressure and also while operating in an unloaded condition. While I have described the invention as used in a compressor operating above atmospheric pressure it will be understood that the invention is equally applicable to compressors or vacuum pumps in which the pressures are below atmospheric.

What I claim is:

1. A regulator for steam driven com-

5   pressors comprising in combination, a steam valve for admitting steam to operate said compressor, speed operated means to control the movement of said valve, a pilot valve
10   and an unloader, two independent pressure operated means to control the movements of said valve, one of said latter means operating through said pilot valve controlling the unloader, the other said means being connected to the discharge conduit of said compressor, means to limit the closing movement of said valve by said pressure operated means, and means to adjust said pressure operated means to operate at different pressures.

20   2. A regulator for steam driven compressors comprising in combination, a valve for admitting steam to operate said compressor, speed operated means to control the movements of said valve, a pressure operated means to control the movements of said valve directly connected to the compressor discharge conduit, an unloader, and a supplementary pressure operated means to control the movements of said valve when a maximum receiver pressure is maintained and the unloader is operated.

25   3. A regulator for steam driven compressors comprising in combination, a valve for admitting steam to operate said compressor, an unloader for said compressor, a pressure operated means directly connected to the compressor discharge conduit to control the movement of said valve at a predetermined pressure when the compressor is

operating under its load, and a supplementary pressure operated means to control the movement of said valve when said compressor unloader is in its unloading position.

4. A regulator for steam driven compressors comprising in combination, a valve for admitting steam to operate said compressor, an unloader for said compressor, speed operated means to control the movements of said valve, a pressure operated means to control the movement of said valve at a predetermined discharge pressure when the compressor is operating under its load, and a supplementary pressure operated means to control the movement of said valve when said compressor unloader is in its unloading position.

5. A regulator for steam driven compressors comprising in combination, a valve for admitting steam to operate said compressor, an intake unloader for said compressor, a pressure operated means to control the movement of said valve at a predetermined pressure when said compressor is operating under its load, a supplementary pressure operated means to control the movement of said valve when said intake unloader is closed to unload said compressor, and a centrifugal operated means to close said valve when the speed of the engine exceeds a predetermined maximum.

In testimony whereof, I hereto affix my signature.

WARD RAYMOND.
